US00D701178S

(12) **United States Design Patent**
Wisniewski et al.

(10) **Patent No.:** US D701,178 S
(45) **Date of Patent:** ** Mar. 18, 2014

(54) **WALL MOUNTED BUTTON PANEL**

(71) Applicant: **Crestron Electronics, Inc.**, Rockleigh, NJ (US)

(72) Inventors: **Stanley Wisniewski**, Pompton Plains, NJ (US); **Doug Jacobson**, Oradell, NJ (US)

(73) Assignee: **Crestron Electronics Inc.**, Rockleigh, NJ (US)

(**) Term: **14 Years**

(21) Appl. No.: **29/460,483**

(22) Filed: **Jul. 11, 2013**

Related U.S. Application Data

(62) Division of application No. 29/394,307, filed on Jun. 15, 2011, now Pat. No. Des. 686,168.

(57) **CLAIM**

The ornamental design for a wall mounted button panel, as shown and described.

DESCRIPTION

FIG. 1 shows a front elevational view of a first embodiment of a wall mounted button panel, with elements in dashed lines forming no part of the claimed design.

FIG. 2 shows an isometric projection of the wall mounted button panel of FIG. 1, with elements in dashed lines forming no part of the claimed design.

FIG. 3 shows a left side elevational view of the wall mounted button panel of FIG. 1, with elements in dashed lines forming no part of the claimed design.

FIG. 4 shows a right side elevational view of the wall mounted button panel of FIG. 1, with elements in dashed lines forming no part of the claimed design.

FIG. 5 shows a top plan view of the wall mounted button panel of FIG. 1, with elements in dashed lines forming no part of the claimed design; and,

FIG. 6 shows a bottom plan view of the wall mounted button panel of FIG. 1, with elements in dashed lines forming no part of the claimed design.

1 Claim, 4 Drawing Sheets
